GERHARD WOLFRAM, OF DESSAU, GERMANY

PORTABLE WORK BENCH

Application filed April 4, 1931, Serial No. 527,817, and in Germany April 11, 1930.

Portable work benches which are supported on a tripod are already known. Normally one leg is pivoted to the work table so that it can be swung into position adjacent to the other legs. In many appliances of this kind a metal base plate or the like is pivotally connected with the foot of the tripod and serves as a pedestal on which the operator stands. As in the known tools the individual devices, for example, a vise, a pipe-clamp or pipe bending devices, are rigidly secured to the tool, only a limited number of operations can be carried out with the said known appliances. A further disadvantage resides in that the rigidity of the appliance is small in consequence of being carried on a tripod and of being pivotally connected with the pedestal, so that operations which require the expenditure of considerable force cannot be carried out with the known appliances. Further the known appliances are collapsible only to a limited extent and even in the collapsed condition are bulky articles occupying considerable space.

Apart from the last mentioned disadvantage the same drawbacks are also present in the form of the tool in which a tool box serves as a supporting frame and the lid of the box is used as a pedestal.

The object of the invention is to provide an appliance which avoids the disadvantages of the known arrangements and which in particular is so constructed that operations of every kind, including those involving the expenditure of considerable force, can be carried out. Furthermore the novel appliance satisfies the requirement that when not in use it can be collapsed so as to occupy the smallest possible space so that it can be simply packed, conveyed and stored.

With this object in view the invention resides essentially in an appliance consisting for example of two vertical pillars and a stay, which appliance is mounted on a base and is rigidly secured thereto and wherein the individual dismountable components of the appliance as well as the tools can be accommodated within or pivoted into the base, which is constituted as an ordinary closed box with a plank or the like closing its base and

a cover, preferably in the form of a lid, covering its upper surface.

Further features of the invention are set out below in the detailed description with reference to the drawing.

The technical advance afforded by the invention resides in that the weight of the operator utilizing the appliance counteracts the forces which arise and in that the appliance is in itself rigid so that it is not necessary to provide any additional loading or anchoring to the ground or to take any other precautions for ensuring stability. In particular the appliance makes it possible to carry out heavy operations such as bending of wires and sheets or hammering operations.

A further important advantage resides in that in the collapsed condition, the appliance has the form of a completely closed cabinet or box. Thus the appliance occupies only a very small space and can be transported without special packing or the like and can be stored in a convenient manner in occupied rooms or workshops or stacked on lorries and the like. In consequence of the construction according to the present invention the appliance can be utilized in an extremely large number of ways and in consequence of its large base may, for example, also be used in rooms where it is necessary to avoid damaging the floor.

One embodiment of the invention is shown by way of example in the accompanying drawing in which:

Fig. 1 shows an elevational view of the appliance erected ready for use, the walls of the base frame being shown in section.

Fig. 2 shows a plan view of the appliance in the collapsed state.

Fig. 3 shows a view of the upper portion of the appliance as seen from the front.

Fig. 4 shows a side view of the upper portion of the appliance with the tools in different disposition.

The appliance consists of a metal frame 1 in the form of a closed figure, for example a rectangle. A longitudinal rib 1' extends through the interior of the frame 1. The base of the frame is closed by a wooden plank 2 or the like. The upper surface of the frame

carries a covering 3, 4 the plate 3 consisting of two flaps or lids hinged to the frame 1 by means of hinges 5. The plate 4 is also divided but the two flaps 4 are secured to the frame by means of devices 6 in such manner as to be readily detachable so that the two flaps 4 can be entirely removed from the frame.

The cross section of the walls of the base frame 1 is also of substantially rectangular profile, provided however with an upwardly and downwardly directed rib or flange. The essential purpose of these ribs is to constitute an edge protection for the base covering 2 and the covering plates 3 and 4. Moreover the ribs facilitate the securing of the hinges 5.

A framework is disposed above the base frame 1. This framework consists essentially of two pillars 8 which are mounted on the base frame 1 and are reinforced by transverse struts 9, together with struts 12. The lower transverse strut 9 is adjacent the base of the pillars 8 and is provided with a headed screw 9' by means of which the pillars 8 are secured to the rib 1'. The pillars 8 are preferably disposed laterally on the frame 1 or on the rib 1' to such an extent that the two covers 3 or 4 can be swung downwardly into position to serve as a pedestal or platform for the operator. The upper transverse strut is provided with a bearing 10 to accommodate the transverse member 11. The transverse member 11 unites the two struts 12 holding the two pillars 8 rigid with respect to the base. The struts 12 are pivotally mounted on the frame 1 by means of pivot pins 13. Adjacent the pins 13 the two struts 12 are connected by a transverse strut 14. In the collapsed condition (Fig. 1) the transverse strut 14 engages in a recess 15 in the longitudinal rib 1' whereas the transverse member 11 is accommodated in a corresponding recess 16 in the longitudinal rib 1'.

The upper ends of the pillars 8 as well as the lateral ends of the transverse member 17 are slotted and constructed in known manner as clamping sleeves so that they can accommodate and be used for securing the most diverse tools. The construction of the upper ends of the tubes as clamping sleeves makes it possible to change the tools rapidly and conveniently. Furthermore the devices can readily be pivoted in their mountings and brought into the most varied positions.

In Fig. 1 a vise 18 is mounted on the left hand pillar whereas the cover 4 is carried on the right hand pillar to constitute a table.

Fig. 3 shows the appliance in use as a lathe. In this case a bar 22 is inserted in the transverse member 11. By means of a pedestal bearing 21 a motor 19 is carried on the bar 22. By means of two T shaped members 23 a tail stock 20 is secured on the opposite end of the transverse member 11. In the illustration

the column 8 carries a table formed by a cover plate 4 but a tool slide can be provided in place of the table.

In the arrangement according to Fig. 4 the bar 22 is inserted in one of the pillars 8. By means of the bracket 21 a motor 19 is mounted on the bar 22 in such manner that its shaft is vertical so that in this way the appliance can be utilized as a vertical boring machine.

Between the two pillars 8 is disposed a winch gearing 24, 25, 26 which may be constructed in the customary manner. Mounted on the shaft 26 is a gear wheel engaging in a rack 25. Outside the housing for the rack is provided the usual ratchet wheel and pawl. The shaft 26 terminates in a rectangular head on which can be mounted an operating handle for operating the winch mechanism. The handle may also be used for operating all devices which require such a drive. For example cutters can be associated with the rack so that by means of the recesses 27, 28 the device can be used at the same time as a shearing appliance for wires, sheet metal or profiled iron bars. In a similar manner the device can also be used for driving a press, a shaft straightening device, an embossing device and the like.

In conjunction with a dynamometer the winch device may be constructed in a simple manner to actuate the appliance for testing materials. As shown for example in Fig. 1 such an arrangement may comprise a plate 29 disposed at the lower end of the rack 25. Between this plate and a buttress 29' is inserted a bar 30 which is to be tested for resistance to pressure. For tension tests the rack is provided on the lower side with a hook 31 the article being tested for tensile strength being secured to the hook 31 and to a corresponding hook 31 disposed on the lower transverse strut 9.

If necessary the device comprising the pillars 8 and the winch gear 24, 25, 26 may be separated from the frame of the appliance and used independently for load raising purposes, for example for lifting lorries and the like.

The appliance, when collapsed, is accommodated in the interior of the frame 1 as are also the individual tools 18, 19, 20 together with the auxiliary appliances 22, 23 etc. so that in the collapsed state the appliance is in the form of a completely closed flat cabinet or box which can be held closed by means of bolts 32 or similar devices. In order to damp the noises occurring during operation sound dampers are provided at appropriate points.

I claim:-

1. A portable work bench comprising a smooth sided and shallow box-like base member to be placed on a horizontal surface; and a plurality of pillars and struts adapted

to be secured to the base member when in use to form the work bench and which are collapsible so that the pillars and struts may be placed in the base member when the bench is knocked down for transport or when not in use and said base member acting as a platform for an operator of the work bench.

2. A portable work bench comprising a smooth sided and shallow box-like base to be placed on a horizontal surface, a pair of pillars, means for securing said pillars to the base so as to stand upright thereon, and a member having one of its ends pivoted to the base near one end thereof and adapted to have its other end secured to the said pillars to brace them securely, said member being foldable about its pivot into the interior of the base when not in use as a brace, and tools supported in operative position upon said pillars, and said base member acting as a platform for an operator of the work bench.

3. A portable work bench comprising a collapsible frame for supporting bench equipment, means for bracing the frame in its erected position, a base element on which said frame and brace are mounted and into which they are adapted to be lowered when the frame is collapsed, and a bottom and a top cover for the base element forming in conjunction therewith a smooth-sided shallow box completely enclosing the brace means and the frame in its collapsed condition.

4. A portable work bench comprising a collapsible frame for supporting bench equipment, means for bracing the frame in its erected position, a base element on which said frame and brace are mounted and into which they are adapted to be lowered when the frame is collapsed, and a bottom and a top cover for the base element forming in conjunction therewith a smooth-sided shallow box completely enclosing the brace means and the frame in its collapsed condition, the frame in its erected position being so located on the base element that the latter constitutes a platform on which a bench operator may stand while manipulating the equipment.

5. A portable work bench comprising a shallow rectangular base frame having side walls and a central rib, a collapsible frame for supporting bench equipment, means for securing said frame to the central rib of the base frame, means hinged to said base frame near an end thereof for bracing the equipment supporting frame when it is erected, said brace means and equipment frame being capable of being lowered into the base frame, a bottom for the base frame, and a top cover for the base frame capable of forming a platform for an operator working at the erected bench, said base frame with its bottom and top cover forming a shallow smooth-sided box into which the equipment frame,

brace means and any desired equipment can be completely enclosed in their collapsed and disassembled condition.

In testimony whereof I have affixed my signature.

GERHARD WOLFRAM.
